UNITED STATES PATENT OFFICE.

ZOLTAN MOLNAR, OF WELAND, ONTARIO, CANADA, ASSIGNOR OF ONE-FOURTH TO
MIHALY SZABO CZORBOY, AND ONE-FOURTH TO MIHALY GREBEZ.

AUTOMATIC RAILROAD GATE.

Application filed March 4, 1927. Serial No. 172,628.

This invention relates generally to a safety device for railroad lines, and has more particular reference to a novel automatic railroad gate for use at points where roads cross the rail tracks.

The invention has for an object the provision of a novel automatic railroad gate which will slowly close as a train approaches the gate, and which will slowly open after the train has passed.

For further comprehension of the invention and of the objects and advantages thereof, reference will be had to the following description and accompanying drawing, and to the appended claims in which the various novel features of the invention are more particularly set forth.

Referring to the drawing forming a material part of this disclosure:

Fig. 1 is a perspective view of a portion of a railroad track to which the invention is applied, and for clearness certain details are omitted from this view.

Fig. 2 is a transverse vertical sectional view taken on the line 2—2 of Fig. 1.

Fig. 3 is a perspective detail view of a switch used in this invention and applied to a fragmentary portion of a rail.

Fig. 4 is a fragmentary side detail view of the top weight of the invention device.

Fig. 5 is a side view thereof looking in the direction of the arrows 5—5 of Fig. 4.

Fig. 6 is a fragmentary side detail view of the bottom, or counterweight of the device, viewed from the same side as the weight illustrated in Fig. 4.

Fig. 7 is a side view thereof looking in the direction of the arrows 7—7 of Fig. 6.

Fig. 8 is a fragmentary side view of the weights hooked together.

Fig. 9 is a schematic diagram of a portion of the invention device, and the wiring therefor diagrammatically applied thereto.

Fig. 10 is an enlarged fragmentary sectional view, taken on the line 10—10 of Fig. 2.

The reference numeral 10 indicates generally a portion of a railroad track crossing a road 11, and a train 12 is shown on the track just past the road. Positioned on each side of the tracks and across the road 11 are posts 13 formed at their tops with U-shaped members 14. Rods 15 are pivoted near one end, as at 16 to one of the U-shaped members 14 while the other ends of the rods are engage-

able in the other U-shaped members. The rods 15 have attached to the ends nearest the pivot point of the rods, flexible cables 17 guided over pulleys 18 and secured to the top of a weight 19 formed with grooves 20 engaged by vertical rails 21 in a dugout 22 near one of the rails 10. The parts are so constructed that the weight 19 is vertically slideable in the dugout 22, and when at the top of the dugout, the rods 15 are downward as shown in Fig. 1, while when the weight 19 is in a position indicated by the dot dash lines 23 in Fig. 2, the rods 15 are in a raised position indicated by the dot dash lines 15' in Fig. 1.

Communicating with the dugout 22 is a cavity 24 extending cross-wise of the rails 10, and having an upwardly directed portion 24' terminating near the rail 10 remote from the dugout 22. A finger 25 projects from this cavity to a little above the top of the rail and is adapted to be depressed by the flange of a wheel of the train 12 as the train passes by. A vertical lever 26 has a finger 25 at its upper end, and is housed in cavity 24', the lower end of this lever being connected to one end of a bar 27 in cavity 24 and the bar 27 is pivotally mounted intermediate of its ends. The other end of the bar 27 is pivotally connected to the bottom of a counterweight 28 formed with side grooves 20 engaged by the rails 21. Resilient bumpers 29 are at the bottom of dugout 22 and are adapted to support the counterweight 28 in its lowermost position.

The top of the counterweight 28 is provided with a post 30 pivotally supporting a hooked member 31 by means of shaft 32, and spring 33 connected between the weight 28 and a portion of the hooked member 31 below the pivot point, serves to normally urge the hook member in a vertical position, by abutment against stops 34 projecting from the top of the weight.

The bottom of the weight 19 is provided with two posts 35 between the lower ends of which a hook member 36 is pivotally supported. A spring support post 37 projects from the weight, and spring 38 acts between the bottom of the post and the end of the hook member 36 to normally maintain the hook member 36 in a horizontal position. The end of the hook member 36 having the spring 38 attached, projects under an arm 39 pivoted as at 40 to the lower

end of an arm support 41 projecting from the weight 19. The other end of the arm 39 is urged upwards against a stop arm 42 by the action of a spring 43 acting between the stop arm and the arm 39, the stop arm projecting from the bottom of the weight 19. A latch member 44 engages under the arm 39 locking that side of the arm from downward motion. This latch member 44 is supported intermediate of its ends by a latch arm support 45 depending from the weight 19. A solenoid 46 suitably supported from the weight 19 is adapted upon being energized to draw the top of the latch member so that the latch member frees the arm 39 permitting downward motion thereof. The hook member 36 is formed with a cam surface 47 adapted to bend the hook member 31 on its pivot 32 against the action of springs 33, when the counterweight 28 is forced upwards, so that the hook member 31 engages and locks onto hook member 36.

Projecting from the top of the weight 19 are horizontal arms 48 connected to cylinders 49 of dash pots having coacting cylinders 50 equipped with air by-passes 51.

At two points in one of the rails 10, one of the points being positioned considerably ahead of the cross road 11, and the other behind the cross road 11, certain switches are located, generally referred to by numerals 52 in Fig. 1, while Fig. 3 shows details thereof. The rail 10 is broken, and in the break there are a pair of insulators 54 and 55, between which a conductor 56 is slidably arranged. The conductor 56 is normally urged upwards by a spring 57, so that the top of the conductor projects slightly above the rail. Terminals 58 are attached to the side of the conductor.

A source of electric current, such as battery 60, has one lead 61 grounded to that portion of rail 10 between the switching devices 52. The other lead 62 is connected with solenoid 46, this lead 62 being very slack to permit of the weight 19 moving as necessary in the dugout. A branch lead 63 from the lead 62 contacts with a contact 64 on the side of the weight 19. From solenoid 46 the circuit continues through lead 65 to a contact 66 on the weight 19. The contact 66 is engageable with another contact 67 supported from the wall of the dugout 22, thereafter the circuit continues through lead 68 to one of the terminals 58 of switch 52, while branch 69 from 58 connects with terminal 58 of the other switch 52. A branch 70 from lead 68 connects with a solenoid 71 upon being energized being capable of moving an arm 72 to release weight 19 from its uppermost position. This arm 72 is pivotally attached to the side of the dugout 22 and urged outwards to lock the weight 19 in raised posi-

tion by a spring 73 coaxially on the pivot of the arm. The circuit continues from solenoid 71 through lead 74 to a contact 75 on the side of the dugout 22. Contacts 64 and 75 engage each other when the weight 19 is in its uppermost position.

Concerning the operation of the device, attention is directed that normally with no trains in sight of the gate, the arms 15 of the gate are in a position indicated in Fig. 1 by dot-dash line 15'. The weight 28 is hooked to the bottom of weight 19 which is in its lowermost position as shown in Fig. 9. When a train approaches the gate its wheels ride over one of the switches 52, depressing conductor 56 and short circuiting the insulator 54 so that a complete circuit exists from the battery 60, lead 61, rail 10, train wheel, conductor 56, lead 69, lead 68, contact 67, 66, lead 65, solenoid 46, and lead 62 to battery 60. The energized solenoid 46, draws the top of latch 44 so that the bottom of the latch 44 moves from under arm 39. The weight of weight 28 transmitted through the hooked member 31 moves the contacting end of hook member 36 downwards, since the other end of the hook member 36 may move upwards moving one end of arm 39 upwards, and the just released portion of the arm moves downwards. The weight 28 then falls to the bottom of the dugout against the bumpers 29. Spring 43 acts to replace arm 39 to its original position, spring 38 acts to replace hook member 36, and a tension spring 45' acts to replace latch member 44. The weight of the rods 15 act to move the weight 19 upwards to its top position, since this weight is not sufficient to hold the rods 15 in a nearly vertical position. The dash pots connected to the weight 19 regulate the speed of the decline of the rods 15. Near the rods 15, bells 76 are located, and any suitable means not shown on the drawing may ring these bells giving warning that the rods 15 are coming down.

By the time the train reaches the road 11, the bars 15 have closed the road. The flanges of the wheels of the train, pass and depress finger 25, moving lever 26 downwards, which move one end of lever 27 downwards. The other end of lever 27 moves the weight 28 upwards, and hooked member 31 catches on the hook 36 so that weight 28 is attached to weight 19. The arm 72 holds the weight 19 in its top position.

As the train passes over the other of the switches 52, the conductor 56 is depressed short circuiting the insulator 54 so that a complete circuit exists from the battery 60, lead 61, train wheel, conductor 56, lead 68, 70, solenoid 71, lead 74, contact 75, 64, lead 63, 62, and battery 60. The energized solenoid 71 moves arm 72 against the action of

spring 73, releasing weight 19, and the released weights slowly descend due to the dash pot action of the dash pots attached to weight 19. The rods 15 are raised to the 5 position indicated by 15' and this stops the downward motion of the weights. The device is now in its original position, and set for the next train. Red lights may be equipped on the gates for night signalling.

10 While I have illustrated and described my invention with some degree of particularity, I realize that in practice various alterations therein may be made. I therefore reserve the right and privilege of changing the details of construction or altering 15 the arrangement of the correlated parts without departing from the spirit or the scope of the appended claims.

Having thus described my invention, what 20 I claim as new, and desire to secure by United States Letters Patent is:

1. An automatic railroad gate, comprising a gate, a pair of weights to operate the gate, means for releasing the bottom one of 25 said weights to close the gate, means for reattaching the weights leaving the gate closed, and means for releasing both of the weights to open the gate.

2. An automatic railroad gate, comprising 30 a gate, a pair of weights to operate the gate,

means for releasing the bottom one of said weights to close the gate, means for reattaching the weights leaving the gate closed, and means for releasing both of the weights to open the gate, the top one of said weights 35 being associated with dash pot action.

3. An automatic railroad gate comprising a gate, a flexible cable connected thereto, a pair of weights to operate the gate, the top weight of said pair of weights being connected to the cable, means for releasing the bottom one of said weights to close the gate, 40 means for reattaching the weights leaving the gate closed, and means for releasing both of the weights to open the gate. 45

4. An automatic railroad gate, comprising a pair of gates, flexible cables connected to each of the gates, idler pulleys for guiding the cable, a pair of weights to operate the gates, the top weight of said pair of weights 50 being connected to the cables, means for releasing the bottom one of said weights to close the gate, means for reattaching the weights leaving the gate closed, and means for releasing both of the weights to open 55 the gate.

In testimony whereof I have affixed my signature.

ZOLTAN MOLNAR.
